Joseph M. Truman vs George Truman, *Administrator* *de* *...*

Sittins Portland

The whole approach in the Saxon Patent and in the part of the same & also
my application to the Board of the Patent Office 16. February and George the
16th. Thereafter these improvements in Saxon's Patent are as follows
for Saxon.

see whom it may concern. Be it known that the Joseph
A. Turner and George Turner of Penn Township in the County of Philadelphia
have invented an improved Pump for the burning of coal, bottom, Spirit
or any of the combustible. Solid, Liquid, or gaseous combustibles
naturally found which Pump is constructed by us the dimensions
of the said Spirit gas Pump and intended to employ it for the
manufacturing of Brick, Stones, Public Buildings, Halls or other places
where artificial light may be required and see to have
by structure that the following is a full and ^{exact} description thereof by
which being had to the drawings which accompany and make
a part of this Specification — We call our Pump a Gas Pump
because there is a part of it which we designate the retort or
Gas Generator in which the vapor arising from the burning brick
or rocks is to be decomposed and prepared for the immediate and
perfect combustion with mixture with a due proportion of natural
plastic air in a way to be presently described — by 1° in the accompanying
drawings is a vertical section somewhat in perspective of the whole apparatus in one of its forms showing a
Pump which may be suspended in a store or elsewhere as
is the case in houses which is to contain the air or other material
it has a bottom and sides like the common Milk Pump & an
air or vapor chamber of brass or copper so constructed that
these are soldered to the bottom of the Pump by their lower edges
whilst they incline towards each other at their upper ends to
bring them plumb when upright, with bottom and each other or

7843X

merely. - C is the part called by us the Retort or Generator
or Fig 2, a section of the bottom of the bell jar sometimes
used by us. It is a rim of brass or other metal which may
be about three fourths of an inch wide, & if we use two concave
pieces of metal with these concave sides to meet together as
each other thus leaving a channel or space between them they
are both edged, or otherwise joined to the rim d. - The upper
plate f. has a round or other shaped orifice in its centre generally
from three eighths to half an inch in diameter - its inner edge being
turned up as shown in the sketch. Sometimes instead of one we make
several orifices, their diameter and form admitting of considerable
variation whilst their capacity or area is a point of considerable impor-
tance. In the lower plate e. a single orifice is made which may be
an inch or more in diameter or of such size as will take in the neck
or necks at the upper ends of the tubes or burners. Although we prefer
to make the retort further. Measures described or nearly so we do not an-
- give ourselves trouble but vary this also in different ways. Sometimes
we use a single plate f. containing the plate e. Fig 2 in which case
it may be flat or concave instead of convex still having the holes
holes in the centre - As the lower edge of the rim d. is not intended
to come into contact with the air or other material in the reservoir of
the Sampur, the air of the atmosphere is freely admitted under
it. It will strip with the gas, formed in the retort or generator and
afford combustion but the rim d. may be perforated with holes
sufficiently numerous to let the edging of the plates, &c. rest
upon legs sometimes used to support the retort or generator
within the reservoir. When taller or other hard some fluid substance
is employed these legs should be made of stout copper to
serve as heaters that being the best conductor among the cheaper
metals - Instead of these legs we commonly use spring pieces
h. & wires to push into sockets rising from the inside of the reservoir
or supply other convenient means of supporting the retort. It is well
known to be able to raise & lower it for heating which will prevent

appear under the spring and socket, ready to allow the flame which is to ascend through the orifice in the plate, to be burnt. A glass chimney is such as is commonly used with lamps, but this is to be surrounded by a metallic or other tube or chimney, the outer end of which the glass chimney passes. This addition will be eliminated in illuminator case in case of lamps, is of practical importance in the Lamp, which we have described. In Samples of the chimney size the length of the illuminator should be from twelve to sixteen inches and of about two inches in diameter, varying of course with the size of the Lamp, and the consequent enlargement or diminution of the flame. When this Lamp is to be used the racks are to be light and should be so drawn up as to sum with a full large frame. The rest or generator is then brought down when say to a distance of from one half to one fourth of an inch from the neck, when a flickering blue flame will ascend through the upper orifices of the upper plate when more than one plate is employed, the light from which will be very full and without smoke. The glass chimney is then to be placed over the frame resting on the generator between small projecting pins, this will produce a strong yellow flame rising to the top of the chimney with much smoke. The illuminator is then added which produces a clear-brilliant stream of a blue flame according to the height of from four to six inches and without any smoke whatever. We have heretofore described the general construction of our illuminator of using our Lamp some have indicated some of the improvements which may be made in it in more detail referring to which the principle of its best construction and action will remain the same.

What we claim as our invention is the employment of that part which we eliminate the neck and in the way heretofore described consisting of one or more plates to be let down upon the flame and over claim the lengthening out of the glass chimney by means of the illuminator addition which the combustion will then be rendered

7843X
I would say that although this illuminator may bear
some resemblance to a chimney or tube for carrying off smoke which
is in common use you know. Scrupit ^{and general good effect} is applied to effect another and
a very different object, namely the entire destruction of the smoke
by the perfect combustion of the carbonaceous matter of the gas. The
claim then therefore not allowed a chimney but in combination
with the generator and gas chamber for the purpose hereinbefore
set forth in a Scrap of construction.
